(57) **CLAIM**

We claim the ornamental design for an equipment display and storage container, as shown and described.

DESCRIPTION

FIG. 1 is a top perspective view of a equipment display and storage container of the present invention;

FIG. 2 is a left side view thereof;

FIG. 3 is a front view thereof;

FIG. 4 is a rear view thereof;

FIG. 5 is a top view thereof; and,

FIG. 6 is a bottom view thereof.

The right side is a mirror image of the left side and is not shown. The ornamental design which is claimed is shown in solid lines in the drawings. Any broken lines in the drawings are for illustrative purposes only and form no part of the claimed design.
